UNITED STATES PATENT OFFICE.

ALEXANDER SMITH, OF NEWPORT, RHODE ISLAND.

STOVE-LID LIFTER.

No. 901,844.

Specification of Letters Patent.

Patented Oct. 20, 1908.

Application filed June 5, 1908. Serial No. 436,933.

To all whom it may concern:

Be it known that I, ALEXANDER SMITH, a citizen of the United States, residing at Newport, in the county of Newport and State of Rhode Island, have invented new and useful Improvements in Stove-Lid Lifters, of which the following is a specification.

This invention relates to an improved stove-lid lifter, its object being to provide a device of this character whereby a stove-lid may be conveniently engaged and held against any possibility of slipping and falling, and which is adjustable to engage the sockets of lids of different sizes.

15 The invention consists of the features of construction, combination and arrangement of parts hereinafter fully described and claimed, reference being had to the accompanying drawing, in which:—

20 Figure 1 is a side elevation of a lid-lifter embodying my invention, showing the same engaged with the socket in a lid, a portion of the latter appearing in section. Fig. 2 is a bottom plan view of the gripping jaw. 25 Fig. 3 is a side view of the same. Fig. 4 is a top plan view of the body or handle of the lifter.

Referring to the drawing, the numeral 1 designates the body or handle of the lifter, 30 which is preferably longitudinally curved in the usual manner, and is provided at its lower forward end with a lifting projection or blade 2. The handle is longitudinally channeled to provide a recess in the underside thereof to receive a supplemental handle or lever 3 adapted to partially fold therein. The handle or lever 3 is provided at its lower forward end with a gripping jaw 4 having a rear toothed or serrated surface 5, and is 35 formed at a point above and in rear of said jaw with an upwardly projecting lug 6 formed with a series of openings 7. The lug 6 projects upwardly and outwardly through a slot 8 formed in the handle 1, and extending transversely through one of the openings 45 7 therein is a pin 9 bridging across the slot 8 and serving to retain the lug in position and pivotally mount the lever 3 upon the handle 1. By passing the pin 9 through one 50 or the other of said openings 7 the jaw 4 may be disposed closer to or farther from the lifting blade 2 for coöperation therewith in adapting the device for application to the differently sized sockets of different sizes of 55 stove-lids. A coiled expansion spring 10 is

housed within the handle 1 and bears upon the upper surface of the lever 3 to normally retract the jaw 4 or swing it toward the lifting blade 2.

In operation, the jaw 5 is adjusted to suit 60 the particular size stove-lid, and the forward end of the tool is then applied in the usual manner to dispose the blade 2 and jaw 4 within the socket of the lid, with the blade 2 disposed beneath the cross bar of said 65 socket and the toothed surface 5 of the jaw bearing against the outer or rear wall of the socket. When the operator grasps the handle 1 and exerts an upward pressure on the lever 3, the jaw 4 will be forced rearwardly so that its toothed surface 5 will grip the said wall of the socket, thus rigidly connecting the lid and lifter, so that any 70 possibility of the lid slipping or becoming displaced and falling while it is being handled will be avoided.

75 From the foregoing description, the construction and mode of use of my improved lid lifter will be readily understood and its advantages appreciated. As long as the upward pressure of the hand is exerted on the lever 3 the jaw 4 will be projected to grip the lid. When the pressure is removed, the expansive action of the spring 10 will throw the jaw out of engagement with the wall of 80 the socket, leaving the lifter free for ready removal.

85 Having thus fully described the invention, what is claimed as new is:—

1. A lid lifter comprising a handle having 90 a lifting blade, a lever pivotally mounted upon the handle and provided with a toothed gripping jaw for coöperation with said blade, and a spring disposed between the handle and lever and operating to normally 95 hold the jaw retracted.

2. A stove-lid lifter comprising a handle having a longitudinal recess in the underside thereof and provided with a lifting blade, a lever pivotally mounted upon the handle 100 to fold within said recess and provided with a toothed jaw for coöperation with said blade, and a spring disposed within the recess between the handle and lever and acting upon the latter to hold the jaw normally 105 retracted.

3. A stove-lid lifter comprising a handle provided with a lifting blade, a lever having an adjustable pivotal connection with the handle and provided with a toothed jaw to 110

coöperate with said blade, and a spring arranged to control the movement of said lever in one direction.

4. A stove-lid lifter comprising a handle having a lifting blade and a slot in rear thereof, a lever disposed upon the underside of said handle and provided with a lug projecting through said slot and having a series of openings and formed in advance of said lug with a toothed jaw to coöperate with said blade, a pivot pin adapted to be en-

gaged with any one of said openings to adjustably and pivotally support the lever, and a spring disposed between the handle and lever for moving said lever in one direction. 15

In testimony whereof I affix my signature in presence of two witnesses.

ALEXANDER SMITH.
